SELECTOR SWITCH BRUSH UNIT ASSEMBLY

Gerald Deakin, New York, N. Y., assignor to International Standard Electric Corporation, New York, N. Y., a corporation of Delaware

Original application September 14, 1946, Serial No. 697,148. Divided and this application July 9, 1948, Serial No. 37,753

12 Claims. (Cl. 200—166)

1

This invention relates to new and useful improvements in brush units suitable for assembly into brush sets of selector switches. The present is a division of my application Serial No. 697,148, filed September 14, 1946.

The object of the present invention is the provision of a brush unit simple to make and one that can be readily assembled into the selector structure.

With this object in view I provide the construction which will be clear from the following description, claims and the drawings illustrating several embodiments of the invention.

In these drawings:

Fig. 1 is a view, on an enlarged scale, of one of several brush units entering into a complete brush assembly;

Figs. 2 and 3 show the brush unit of Fig. 1, as viewed from other angles;

Figs. 4 and 4A are enlarged sectional views along lines 4 and 4A, respectively, of Fig. 1;

Figs. 5, 6, and 7 show a modified form of brush unit, as viewed from three sides;

Fig. 8 is an enlarged sectional view along line 8—8 of Fig. 5;

Figs. 9, 10 and 11 are plan and opposite end views, respectively, of a brush holder, and

Fig. 12 is a perspective view showing the novel carriage mounts.

As shown in Figs. 1 to 4A, each brush unit is composed of two distinct complementary segments 32, 33 of suitably tempered spring material as, for example, Phosphor bronze, and each complementary segment is centrally depressed and laterally extended, forming tabs 36, 37, on one segment in juxtaposed relationship to the corresponding tabs 38, 39, of the complementary segment. Backing strips 41, 42 cover these tabs, and are in turn retained in the non-conducting brush holder 43 with which each brush unit is individually provided; the novel retaining means consisting of hairpin-shaped clamping springs 44 covering the end portions of the backing strips 41, 42 and also pressing resiliently against the sides of ribs 46 (see Fig. 4A) integrally formed on adjacent parts of each brush holder 43. Thus each brush unit is effectively retained and positioned in its individual insulating holder. The several units comprising the complete brush assembly are in turn retained in assembled relationship.

The central depressions formed in the brush complements, as above noted, have the advantage of allowing wider movement of the working end portions of the brushes, without introducing any substantial variation in brush tension. Addition-

2

ally, the brush complements are preferably edge-turned along their sloping edges, as indicated at 51 and 52 in Figs. 1 and 4, as this stiffening treatment protects the parts against bowing or warping, and insures maintenance of firm contact pressure upon the stationary circuit parts engaged by the brush ends. The latter are preferably silver-coated along the engaging surfaces, to the degree indicated by the slanting dash lines 53, 54 in Fig. 1; this coating material being preferably applied as an inlay. The brush construction and contour are such as to facilitate production of the brush elements on a multi-slide stamping machine operating upon a continuous strip of metal of selected width, to effect blanking, forming, and tensioning of the brush elements in one continuous series of operations.

The tensioning of the brush elements is such as urge their tips 56 firmly against opposite sides of the particular bus bar or feeder strip 31 of a selector engaged thereby, and to urge their tips 57 firmly against opposite sides of the terminal contact pins 35 of the selector terminal bank engaged thereby in succession as the brush carriage traverses its prescribed path of travel.

To mount a set of brushes in a carriage, rectangular blocks 61, 62 (Fig. 12) are provided at opposite sides of brush carriage chassis 27, the said blocks being of natural or synthetic rubbery material (neoprene being an example thereof) and of a length and width suitable for their proper registry, first with the trunnions 63 (Figs. 1, 9, 10 and 11) projecting from opposite ends of each brush holder—the blocks 61, 62 being apertured, as shown at 64, to receive said trunnions—and secondly, with the space between flaps 28, 29 on the carriage chassis. Each block is secured to the chassis by a spring clamp 66 having a lip 67 to engage a flange 68 of the chassis, and an opposite lip 69 extending around an edge of the chassis. The effectiveness of this arrangement as a vibration-damping support for the brush assembly, as well as its simplicity, can readily be understood from this illustration and description of this presently preferred embodiment.

The brushes are mounted in the carriage 27 with the contacts 56 up to engage the bus bars 31 extending under the top of 27.

Figs. 5 to 8 show a modified type of brush unit utilizing the same form of two-part brush, but a different form of backing, spacing and clamping means therefor, consisting of backing strips 141 and 142, spacers 143, and clamping eyelets 144 to clamp the spring tabs and backing strips 55 in assembled relationship; the strips 141 and 142

having lateral extensions 151, 152 to grip and hold said spacers 143 to the assembly, and longitudinal extensions 163 to fit into the apertures 64 (Fig. 12) of the cushioning blocks 61, 62 as do the corresponding extensions 63 of insulator 5 43 of Figs. 9 to 11. It will be noted that the parts 141, 142, 143, 144 and 163 of Figs. 5 to 8 are substantially comparable in functions to parts 41, 42, 43, 44 and 63 respectively, of Figs. 1 to 4. Accordingly, if desired, the assembly of Figs. 5 to 10 15 8 may be substituted for that of Figs. 1 to 4.

In comparable manner, other substitutions and rearrangements of parts, as well as modifications in the mode of operation, may be resorted to without deviating from the principles of the invention, as herein indicated.

What is claimed is:

1. In a brush unit, a plurality of complementary brush segments having centrally bent portions contacting each other, laterally extending tabs formed by said portions and lying one against another, a pair of insulated backing strips lying against the outer surfaces of said tabs, said backing strips having mounting extensions extending therefrom and formed integral therewith, and means including members engageable with said tabs and backing strips for holding said brush segments in predetermined relationship.

2. In a brush unit for selector switches having feeder strips and terminal pins, an insulating brush holder, a brush wiper on each side of said holder, each wiper having a first and a second restricted contact making end formed to engage a feeder bar and the terminal pins, respectively, each wiper further having a central portion bent to contact with the corresponding portion of the other wiper, bars engaging the central portions of each wiper, and means for attaching the bars to the wipers and to the spacer.

3. The brush unit, according to claim 2, and mounting trunnions projecting laterally from the unit.

4. The brush unit, according to claim 3, and in which the trunnions are integral with the insulating brush holder.

5. The brush unit, according to claim 2, including mounting trunnions extending laterally from the unit, and in which the trunnions are integral with the bars.

6. The brush unit, according to claim 2, and in which the insulating brush holder is provided with an opening within which lie the central wiper portions.

7. The brush unit, according to claim 6, and in which the central portions of the wipers have extended lateral tabs and the bars are within the opening in the brush holder and are riveted to the central portions of the wipers.

8. The brush unit, according to claim 2, in which the insulating brush holder has an opening within which lie the central wiper portions, and means for clamping the bars to the holder.

9. The brush unit, according to claim 2, and in which the brush holder is a strip of insulating material below said bars, which is straddled by the wipers, and the bars are of metal and have lateral extensions thereon connecting them with the holders.

10. In a brush unit for selector switches having feeder strips and terminal pins, an insulating brush holder having a central opening, mounting trunnions laterally projecting from said holder, a brush wiper on each side of said holder, each wiper having a first and a second restricted contact making end projecting beyond the holder and formed to engage a feeder bar and the terminal pins, respectively, each wiper further having a central portion bent to contact within the opening of the holder with the corresponding portion of the other wiper, lateral tabs projecting from each central portion within said opening, triangular segments joining the ends of each wiper with the central portion, the triangular segments and the end having upstanding stiffening edges, bars engaging the central portions of each wiper within the opening, and means for attaching the bars to the wipers and to the holder.

11. The brush unit, according to claim 1, and in which the means for holding comprises rivets through the strips and the central wiper portion and tabs thereof.

12. The brush unit, according to claim 10, and in which the means for attaching comprises clamps fastening the bars to the holder.
